CLAIM

The ornamental design for a wall mountable container holder, as shown and described.

DESCRIPTION

FIG. 1 is an isometric view of a wall mountable container holder according to the present invention;
FIG. 2 is a front elevational view thereof;
FIG. 3 is a first side elevational view thereof;
FIG. 4 is a second side elevational view thereof;
FIG. 5 is a plan view thereof;
FIG. 6 is a bottom plan view thereof; and,
FIG. 7 is a back elevational view thereof.
